CLAIM

The ornamental design for an ergonomic chair frame with elastic bands, as shown and described.

DESCRIPTION

FIG. 1 is a perspective view of the ergonomic chair frame with elastic bands of the present invention;

FIG. 2 is an alternative perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portions of the ergonomic chair frame with elastic bands illustrated in broken lines form no part of the claimed subject matter.
